CONVEYER AND COUCHER BELT PROCESS
AND MACHINE FOR THICKENING PULP

John P. Rich and Elmer R. Burling, Nashua,
N. H., assignors to Improved Paper Machinery
Corporation, Nashua, N. H., a corporation of
Maine

Application April 17, 1939, Serial No. 268,354

8 Claims. (Cl. 210—199)

This invention has to do with a machine and process for reducing the water content of pulp stocks and other similar materials. It deals with an improved method of collecting on the filter surface pulp materials, particularly with and during the latter stage, and of expressing, by pressure, the water or other liquid from the freshly deposited materials so that they may be delivered from the machine as free from water or other liquid content as practicable.

This machine may employ the usual rotating cylinder or drum, the surface of which forms the filter, and which may be covered with fine wire cloth or any other suitable filtering material. This drum or cylinder may be immersed in a tank or vat to which the liquid to be thickened is supplied, the water or other liquid of these materials being drawn through the filter surface by gravity, by suction, or by any other suitable or desired means, thereby separating the liquid from the solid constituents of the material to be thickened.

As the materials are deposited in increasing thickness on the filter surface, the continued movement of this surface through the tank or vat eventually brings the deposit out of the liquid in the vat. At this time, there is still a large amount of liquid in the deposited material, much of which can be removed by compressing the deposit against the filter surface, thereby squeezing out the water or other liquid into the interior of the filter drum, from which it is removed by any convenient means. It has heretofore been customary to use one or more rolls which are pressed against the deposit on the cylinder either by their weight or by springs or by additional weights, so that pressure is placed on the partially solidified pulp layer, which pressure is used to force or express the liquid remaining in the deposit through the filter surface.

These rolls are sometimes made up in sections to take care of the unevenness of the pulp deposit in certain cases, and sometimes a belt or apron, on which rollers or weights are placed, is wrapped over a considerable portion of the drum surface.

Such belts are permeable and are used where it is necessary or desirable to wash the solids deposited on the filter surface by means of fresh water sprayed over the deposit, the belts being effective to retain the deposit on the filter surface and to compress it to a uniform density, whereby the washing is rendered more effective.

This invention is not concerned with the washing of the filter deposit, or with the provision

of a water and air permeable belt through which the wash liquid may pass or to permit air to be drawn through both the belt and deposit, to assist in cleaning or removing the wash water previously sprayed on the deposit, or on the belt.

It has for its object almost a diametrically opposite purpose, namely, to collect or assist in the collection on the filter surface of a deposit of uniform thickness, and of greatly increased quantity, as is hereinafter described more in detail, and further to provide means for expressing the liquid from such deposit progressively, so that the deposit will not be disrupted, and to give time for the liquid to pass through the deposit to the interior of the filter and thus be separated entirely from the deposit on the filter surface.

It is obvious that the foregoing desideratum could not be attained by the use of a permeable belt, as pressure applied by the belt to the pulp deposit would force the liquid in the deposit into and through the belt from which it could readily pass back into the supply from which the deposit is drawn, thereby defeating one object of our invention.

In contra-distinction to these methods, we employ a short section of an impervious flexible material, in the form of a combined coucher and conveyer belt so mounted and arranged in relation to the filter surface, and its deposit that it not only aids in the collection of materials on the filter surface, but also effects a gradually increasing pressure on the deposit so that the liquid remaining therein is expressed through the deposit gradually, and no opportunity is presented for the liquid in the deposit to be pushed along the surface of the deposit ahead of the point where pressure is applied, but rather this liquid is driven or forced directly through the deposit and through the filter surface, effecting its complete and final removal from the deposit.

In describing our invention, reference is made to the following figures:

Fig. 1 shows a conventional type of thickener or filter drum immersed in a tank or vat, with our deposit conveyer arranged to simply express liquid from the deposited material and to remove these materials from the filter surface.

Fig. 2 is a sectional view through the conveyer and its guiding roll.

Fig. 3 shows the preferred form of our device in which the conveyer belt is immersed, at its lowest point, in the mixture in the tank. There is also shown a third or take-up roll, which can be used or not as desired.

In Fig. 1 is a vat or tank of any suitable de-

sign to which the liquid materials P to be thickened are supplied through pipe or opening 2 with the usual conventional baffle board 3 to deflect and distribute these materials uniformly over the entire area of the tank 1. Usually the liquids are maintained at some fixed level W. L., this level varying somewhat without interfering with the operation of the machine. Rotating in the tank or vat 1 is a filter drum 6 covered with some suitable filter material 7 such as wire cloth or screen. The liquid which passes through this screen may pass directly to the interior of the drum, or pass into segmental sections near the exterior of the drum as at 8 from which the liquid is removed by any suitable means commonly employed in machines of this type.

The filter drum 6 may be supported for rotation at its periphery, or it may rotate about a shaft 9 supported with suitable bearings in or on the end of the tank 1. The character of the filter drum, its mounting, or the tank or vat used to supply the material to be thickened, forms no part of this invention and is illustrated herein simply to show a commonly accepted and conventional means for collecting the solids and separating them from the liquids supplied to the tank.

The operation of a thickener or filter drum is old and well known in the art and needs no further description or explanation. However, certain important problems in connection with the use of such a filter drum have not heretofore been satisfactorily solved and these problems deal particularly with the final disposition or removal of the pulp materials from the liquid in the vat, with the removal from these deposited materials, after they leave the vat, of as much liquid as is possible, and with a clean and complete removal of these materials from the filter surface, so that it may again be utilized to receive a fresh deposit or layer of the liquid-permeated pulp.

As the filter drum 6 rotates in the direction of the arrow, the liquid of the mixture of tank 1 flows thru the filter surface 7 leaving a deposit of solids in increasing thickness as indicated at 10a, 10b and 10c and 10d. As the thickness of deposit increases, the resistance to the flow of liquid through this deposit obviously increases, and if the filter drum 6 were turning slow enough, these two forces would eventually tend to balance themselves and deposition on the filter surface 7 would virtually cease. In order, however, that the capacity of the machine may be at its maximum, the cylinder 6 is rotated at a speed in direction of arrow which does not permit the end point of deposition to be reached, but utilizes a period of immersion and deposition time which will deposit the maximum amount of solids on the filter surface in a given time and not permit a portion of the filter surface travel to be wasted by having it moved so slowly that deposition has ceased or has become very slow.

However, one condition occurs which has heretofore been very troublesome, and has interfered with the proper operation of machines of this type, and one of the principle objects of our invention has been not only to obviate and remove entirely this difficulty, but to provide a mechanism which will so operate as to convert this difficulty into an asset, thereby eliminating previous unsatisfactory operation, and at the same time greatly increasing the capacity and usefulness of the machine.

This is accomplished mainly by the arrangement shown in Fig. 3. We have already described

the conventional or normal deposition of solids on the filter surface at points 10a, 10b, 10c and up to point 10d. However, the condition of deposition beyond point 10d or in area II is vastly different from that at any other point in the vat and particularly from that point 10a. The operation of the filter drum 6 acts as a thickener, not only by drawing to its surface and retaining thereon a fairly solid and stable layer or mat of material, but it also draws liquid from the solid materials in the vat which materials are not actually deposited on the filter surface, so by the time that the filter surface passes point 10a the liquid in the tank 1 at area II has become very much thicker than at point 10a and frequently so thick that the solids therein will not adhere to the other materials deposited on the filter surface. It may become so thick, and so dense, that it actually scrapes off some of the materials already deposited, further aggravating the condition in area II and greatly reducing and interfering with the operation and capacity of the machine.

In order to obviate this serious difficulty, we provide means for mechanically removing the thickened material from area II and depositing it on the layer 10c-d, smoothing out said layer and providing a mat of uniform thickness and quantity, consolidating these materials from area II with mat 10c-d, expressing the water or other liquid from both mats, and finally removing them cleanly from the filter surface at point 13.

The coupler and conveyer belt previously mentioned is indicated at 14, this conveyer belt either being carried by a main roll 15 and an idler roll 16 as shown in Fig. 1 or by a main roll 17, an idler and take-up roll 18, and a collecting roll 19, as shown in Fig. 3. It may be guided by flanges 20 on roll 15 or by flanges on other rolls or by any other suitable means.

It will be observed in Fig. 3 that the collecting roll 19 with its conveyer belt 14a is immersed somewhat below the level of the liquid pulp materials P and into the area II where the thickened materials accumulate for reasons heretofore described. The conveyer belt moving in the direction of arrow Y at a speed closely coinciding with surface speed of the pulp mat on the filter surface, tends to draw the thickened pulp materials from area II toward the filter surface by mechanical means, through the motion of the conveyer belt 14a through thickened materials in area II in a direction towards the filter surface 7.

It will be observed that the collecting roll 19 is so mounted that a considerable space is provided between the conveyer belt 14a and the filter surface 7 as indicated at Z. This space at point Z provides room for the thickened materials to enter between the belt and the previously deposited materials 10a to 10d, this space being, in effect, wedge-shaped, tapering upward, and due to the combined motion of conveyer belt 14a and the filter surface 7, with the mat 10d thereon, the thickened materials from area II are drawn from this area into space Z between the conveyer belt 14a and the mat 10d where they are consolidated with this mat. This enables added solids to be removed from the liquid in the vat 1 by the addition of materials at point Z, thereby greatly increasing the capacity of the machine.

Referring to Fig. 3, it will be noted that three areas or zones are indicated on the filter surface as A, B and C. Area or zone A indicates

that section beyond point 10c-d, where normal depositions of solids on the filter surface has practically ceased, and where, without our device, not only would additional deposit or collection of materials be ineffective, but also where materials already deposited might be scraped off for reasons already described.

However, by locating collecting roll 19 as heretofore described, we utilize zone A to mechanically collect additional solids on the already deposited layer, thereby removing them from area 11, rendering zone A again effective to collect solids, thereby increasing machine capacity.

The thick layer or mat or fibres we are thus able to collect on the filter surface still contains a considerable quantity of liquid which it is desirable to remove. In order to retain the filter mat in a firm, even layer to facilitate its removal from the filter surface, it is necessary to express the water from this mat, after leaving zone A, gradually, otherwise the layer will be disrupted and broken, particularly if any attempt is made to force the water from the mat too rapidly, in which case both solids and water will be forced back down through zone A and into area 11, defeating the very object sought and the result already attained, and greatly impairing the usefulness and capacity of the machine. Extra large couch rolls are sometimes used to increase the length of time of compression at any given speed, but it will be readily seen that we have provided a device more effective than even a couch roll of infinite diameter.

By allowing a substantial interval of time during which the mat or cake is compressed with progressively increasing pressure, it is readily possible to extract a greater amount of liquid, and therefore deliver drier solids from the device. This is particularly useful where the liquids contain ingredients which it is desired to separate from the solids and where the liquids have been added to the solids in the vat as in the case of multiple stage pulp washing.

As shown in Fig. 3, the conveyer belt 14a is stretched between the main roll 17 and the collecting roll 19 in a curve or arc tending to compress the pulp layers against the filter surface, with the degree of such compression in zone B being determined by the tightness of the conveyer belt 14a, which is regulated by the tighter roll 18. It will be readily observed that gradually increasing pressure is imparted to the mat throughout zone B in the direction of the arrow, affording opportunity and time for the water still contained in the mat after leaving area A to be expressed through the mat, and through the filter surface 7, instead of being forced backwardly or downwardly into area 11.

After this compression period through zone B, the mat passes directly under the main roll 17 at which time additional pressure is placed on the mat through zone C by either the weight of the roll 17 or such additional weight 21 as may be desirable or necessary. Under certain conditions, it may be desirable to have less weight on zone C than the weight of the roll 17, which may be accomplished by a counterbalancing weight 21a as shown. By suitable arrangement of weights 21 and 21a, it is possible to impart any desired pressure throughout zone C. These weights acting about fulcrum F. After the final compression of the deposited mat in zone C, it will be found to adhere to the conveyer belt 14a more firmly than to the filter surface 7, hence the mat is removed at point 13 passing around roll 17 and

partially around roll 18 (Fig. 3) at which point the mat can be removed by any suitable means such as doctor plate 26. This doctor plate is preferably located at such a point 25 that the natural bending of the conveyer belt 14a around roll 18 tends to loosen the mat from the belt and facilitate its removal. The doctor plate 26 is also located so that any adjustment of belt tension by movement of roll 16 does not materially change the relation of the doctor plate and the belt, or affect the removal of the mat from the belt. In Fig. 1 the doctor plate 26a may be located at any convenient point, but preferably somewhat below the center of main roll 15 and just after or about the time that the belt 14 is leaving the roll on its return to roll 16.

In order to keep the inner surface of the conveyer belt clean and free from pulp deposit, a shower pipe 27 may be located as shown in Figs. 1 and 3 and a shower of water, as indicated, sprayed over the inside of the belt, which water will carry any fibres or other solids washed off the surface of the belt out over the edges of the belt and out over the ends of rolls 16 and 19, thereby keeping the interior of the belt clean.

Where the collecting roll 19 is immersed below the surface W. L. of the liquid, the ends of said roll may be provided with flanges, or the edges of the belt 14a may pass closely between cover plates extending above the surface W. L. so that pulp or other solids are excluded from the interior of the belt. The surplus water from shower pipe 27 running out over the roll flanges or over the top of the cover plates, serves to keep the interior belt surface clean and to prevent pulp materials from entering this area.

It has already been pointed out that the belt 14a is impervious to either water or air, hence the water from shower pipe 27 can in no way find its way to the pulp mat and can in no way interfere or reduce the extraction of water from the mat in zones B and C.

Having thus described our invention, what we claim is:

1. Apparatus of the class described, comprising a container for a mixture of solids and liquids, a filter drum therein adapted to collect a layer or mat of semi-solid material on its surface, a roll mounted above said vat, a second roll mounted somewhat below the level of mixture in the vat, and adjacent the drum surface in the zone in which the drum emerges from the mixture, and having its surface spaced further from the drum surface than that of the first mentioned roll, and an impervious belt stretched between said rolls and adapted to contact the semi-solid material on the surface of the filter drum with increasing pressure as the material moves from the zone adjacent to the second roll to the zone adjacent to the first roll.

2. Apparatus of the class described, comprising a container for a mixture of solids and liquids, a filter drum therein adapted to collect and retain on its surface a mat or layer of semi-solid material, an impervious conveyer belt, a plurality of rolls over which operates said belt, one of said rolls being immersed somewhat below the level of the liquid materials from which the mat on the filter drum is collected, and adjacent the drum surface in the zone in which the drum emerges from the mixture of materials, and having its surface spaced further from the drum surface than that of another of said rolls, means to drive said conveyer or coupler belt at a speed substantially the same as the surface speed of the mat

on said filter drum, and means to remove from said belt the mat which has collected thereon.

3. An apparatus for thickening pulp comprising a vat adapted to contain a liquid-pulp mixture, a filter drum arranged for submergence in said mixture, and having means operable by differential pressure to collect on its surface a layer of semi-solid material from the mixture, means partially submerged in the liquid-pulp mixture, and independent of said differential pressure means to impose additional material upon said drum and upon the material collected thereon, including means to compress and consolidate the material collected by the two means, and to remove the combined, compressed and consolidated materials from the surface of the filter drum.

4. The method of thickening liquid pulp mixtures, which comprises the extraction of a certain portion of the liquid content from said mixture through a filter surface, leaving a layer of uncomplicated semi-solid material deposited thereon, of initially pressing said semi-solid layer at substantially right angles to the filter surface, and while said surface is submerged below the liquid mixture level, of imposing additional and gradually increasing pressure on said semi-solid layer of material in the zone through which the layer of semi-solid material leaves the mixture for gradual extraction of additional liquid content from and through said layer, said liquid being expressed through said filter surface, and of applying further and additional pressure on said layer to effect added liquid extraction from said layer and its removal through said filter surface.

5. The method of thickening pulp mixtures which comprises the extraction of a certain portion of the liquid content from said mixture by a differential head on a filter surface, leaving a layer of semi-solid material deposited on said filter surface, of gathering additional material by means independent of that causing the first deposit, and of consolidating said additional materials with said initially deposited materials by pressure at substantially right angles to the filter surface, of imposing additional and gradually increasing pressure on said materials, said pressure compressing them against the filter surface and effecting gradual extraction of liquid content from and through said material, and through said filter surface, and of subsequently applying additional or greater pressure on said layer to effect further liquid extraction and its removal through said filter surface.

6. Apparatus of the class described comprising a vat containing a mixture to be filtered, a filter drum adapted for immersion and rotation in said vat, means to remove a portion of the liquid from said vat mixture through the filter drum surface, the remaining thickened material being partially retained on and moving with said drum surface with other thickened material being closely adjacent to said drum surface but not attached thereto, a pair of rolls adjacent said drum surface, and one of which is located adjacent the zone at which the filter drum emerges from the mixture, said roll being partially submerged, and having its surface spaced further from the drum surface than that of the other roll, an impervious belt carried by said rolls and so located by one of said rolls that it is in contact with the thickened vat material both on said filter drum surface and immediately adjacent thereto, and means to move said rolls and said belt in synchronism with the thickened materials collected by cooperative effort of said drum and said belt.

7. Apparatus of the class described comprising a vat, a filter drum in said vat, means to collect on the surface of said drum and accumulate immediately adjacent said surface a mass of partially thickened material, and means adjacent and submerged with respect to the emerging zone of the filter drum surface to collect, compress, and discharge said partially thickened material, said means having a surface adjacent and submerged with respect said drum surface and spaced further from the drum surface at points nearest the mass of material than at points above the material.

8. A pulp thickener comprising a vat containing the mixture to be thickened, a filter drum partially immersed in the vat mixture and rotatable therein, means to collect on the surface of said rotating filter drum and immediately adjacent to said surface at the point where said drum emerges from the mixture a mass of partially thickened material, means comprising a moving belt partially immersed in said mixture adjacent to the zone where said drum emerges therefrom for collecting, compressing, and discharging said thickened material, said belt being so positioned adjacent the surface of the drum as to converge toward said surface in the direction of the movement of the drum and belt as the drum surface passes away from the mixture.
